UNITED STATES PATENT OFFICE.

ELLIS E. LONGFELLOW, OF EL RENO, OKLAHOMA; MARGARET E. LONGFELLOW, EXECUTRIX OF SAID ELLIS E. LONGFELLOW, DECEASED.

LOCK.

Application filed November 8, 1920, Serial No. 422,550. Renewed December 1, 1922.

To all whom it may concern:

Be it known that I, ELLIS E. LONGFELLOW, a citizen of the United States, residing at El Reno, in the county of Canadian and State of Oklahoma, have invented new and useful Improvements in Locks, of which the following is a specification.

My present invention has reference to an improved door lock.

My object is to simplify and improve the existing art by producing a door lock that shall comprise few simple parts and wherein a single bolt is employed for both latching and locking purposes, and in which a key 10 of a particular construction revolves a normally latched barrel to bring an obstructing element carried by the latter to a position to permit of the free operation of the latch bolt on the turning of the knob spindle or 20 to a position to prevent the retraction of the said bolt and hold the same effectively in locking position.

A still further object is the production of a door lock in which the employment of tumblers is entirely dispensed with, and in which the key barrel that carries the bolt obstructing element is disposed directly forward of the knob spindle at the center of the lock casing, and whereby the lock may be 25 inserted in the mortise in a door with either end up; thus obviating the necessity of arranging the lock at a certain position before the same can be inserted in the mortise.

It is a further object to arrange in the lock 30 casing a frame-like member that carries the combined latching and locking bolt, the longitudinal portions of the said member being received in notched lugs and surrounded by springs which exert a tension between the 35 lugs and the outer element of the member on which the bolt is arranged so that the bolt is normally projected through the bolt opening in the casing, the spindle sleeve being provided with the usual laterally projected 40 oppositely directed cam lugs that may be turned in either direction for retracting the latch bolt, while the key barrel is engaged by a guide that carries a spring influenced pin that enters notches in the barrel for holding the same in desired positions, said 45 pin being retracted by the key when the

latter is inserted in the key barrel, and the said barrel having a projecting portion which contacts with the outer element of the frame, when the barrel is turned to one 55 position to prevent the inward movement of the frame, and consequently the inward movement of the bolt, the barrel being also locked by the spring influenced pin in such position.

Many other objects and advantages will 60 present themselves as the nature of the invention is better understood, reference being had to the drawings accompanying and forming part of this application.

In the drawings:—

Figure 1 is an elevation of a door lock 65 constructed in accordance with this invention.

Figure 2 is a similar view with the face 70 plate removed.

Figure 3 is a sectional view approximately on the line 3—3 of Figure 2.

Figure 4 is a sectional view approximately 75 on the line 4—4 of Figure 2.

Figure 5 is a view similar to Figure 2, but showing the combined latching and locking bolt held in locking position.

Figure 6 is a perspective view of the latching bolt and the frame on which it is supported.

Figure 7 is a similar view of the key 80 barrel.

Figure 8 is a similar view of the guide 85 for the key barrel.

Figure 9 is a view of the spring influenced pin carried by the guide.

Figure 10 is a plan view of the body portion of the lock casing with the locking elements removed.

The door lock, illustrated in the drawings, is of the class designed to be received in the mortise of a door, and includes the usual substantially rectangular flanged casing 1 that has its outer edge closed by the usual face plate 2. In the present instance, the face plate 2 is centrally provided with a substantially rectangular opening 3. The side plate of the casing, to the rear of the opening 3 has a round opening 4, notches 5 disposed to the rear and to the opposed sides of the wall provided by the opening 4, a stud

6 to the rear of the notches, a round opening 7 to the rear of the stud and slotted lugs 8 disposed slightly to the rear of the stud and at equi-distance from the sides thereof.

- 5 The combined latching and locking bolt, indicated by the numeral 9 is designed to pass through the opening 3 in the face plate 2, and is centrally secured on a plate 10. The plate 10, adjacent to its ends has arranged thereon rearwardly extending rods 11 which have their free ends connected by a second plate 12. It will thus be noted that the bolt 9 is mounted on a substantially rectangular frame, and the parallel rods 11 of
- 10 the said frame are designed to be received in the slots of the lugs 8. On the rods 11, and exerting a tension between the lugs 8 and the front plate 10 of the frame, are helical springs 13. The springs normally hold
- 15 the bolt projected through the opening in the face plate.

In the opening 7 there is arranged one end of the spindle sleeve 14. This sleeve is provided with the usual laterally projected oppositely directed cam lugs 15 which are designed to separately contact with the rear plate 12 of the frame, when the knob is turned to revolve the spindle in the spindle sleeve 14 to retract the bolt. It has not been

20 deemed necessary to illustrate either the knob or the spindle, the spindle sleeve 14 being provided with the usual squared opening for the reception of the spindle.

In the notches 5 are received two of the 35 fingers 16 which are provided on all of the corners of a cross sectionally U-shaped guide member 17. The guide preferably has its rear wall thickened and its parallel top and bottom walls formed with arcuate depressions 18 at the center thereof. The rear wall of the guide, indicated for distinction by the numeral 19 is centrally provided with a round aperture 20 which receives one end of a pin 21. On the pin is a flange or collar 22 against which a light helical spring 23 contacts. The opposite end of the pin is received in an aperture 24 in the stud 6. The key barrel, broadly indicated by the numeral 25 has one of its reduced ends received in

40 the opening 4 of the lock casing. The barrel, adjacent to its ends is provided with spaced annular enlargements arranged in pairs, or what may be termed flanges, and which are indicated by the numeral 26.

45 These flanges are engaged in the arcuate depressed portions of the parallel or flanged members of the guide 17. The body of the key barrel between the inner guide flanges has a desired number of spaced openings 27 therethrough that enter the right angularly arranged slots that provide the key ways 28 respectively. Any one of these slots is designed to be engaged by the pin 21, so that

50 the key barrel can be held at desired positions in the casing. On the body of the key

barrel there is a lug or projection 29 that is designed, when the barrel is turned to one position, to either contact with or be arranged slightly to the rear of the front plate 10 of the bolt frame, so that the bolt cannot be moved inward of the casing. When in other positions, the other slots 27 receive therein the spring pressed pin 21, so that the barrel cannot be accidentally turned and also whereby a key of a special design must be employed for causing the pin to be retracted out of the openings in the barrel before the barrel can be turned. It is obvious that by differently stepping the key ways in the barrel, varying shaped keys must be employed for engaging and retracting the locking pin before the barrel can be turned to bring the obstructing element thereon into or out of bolt obstructing position. It is also obvious that flat keys must be employed.

Arranged over the elements above described, and closing the opening side or face of the lock casing, is a cap plate 30. This plate is provided with openings to receive the end of the barrel and the end of the spindle sleeve. The plate 30 is further provided with a screw opening which is arranged opposite the stud 6. The stud 6 has a threaded bore, and a screw 31 is inserted through the opening in the plate and enters the threaded bore of the stud, thus locking the plate 30 on the lock casing. The plate 30 has two of its ends flanged inwardly, as at 32, thus insuring the easy and proper arrangement of the said plate on the lock casing.

The plate 30 is also provided with notches 33 that receive therein the fingers 16 on the guide 17 that are not received in the notches 5. In this manner the guide is effectively held against movement in the casing, and it is thought that the foregoing description, when taken in connection with the drawings will fully set forth the simplicity and advantages of the construction, as well as the operation thereof, without further detailed description.

Having thus described the invention, what I claim is:

A door lock including a casing having a face plate provided with a central bolt opening, a bolt arranged therein, a plate secured to the inner face of the bolt and disposed in the casing, rods connected with the plate, a second plate connected to the ends of the rods, notched lugs in the casing receiving the rods, springs on the rods contacting with the lugs on the front plate, a spindle sleeve in the casing having lugs thereon in engagement with the rear plate, a key barrel having right angular key ways therethrough and having spaced annular flanges providing ways and openings between the ways, a lug projecting from the outer face of the barrel, a substantially U-shaped guide removably secured in the casing having its par-

lel members provided with arcuate depressions which are received in the ways, a spring influenced pin passing through the guides and designed to enter one of the apertures of the barrel and to be retracted when the key is inserted in the key way of the barrel to permit of the turning of the barrel to bring

the lug thereof in the path of contact with the front plate of the bolt, and the said spring influenced pin designed to enter another aperture in the barrel when said barrel is in such position.

In testimony whereof I affix my signature.

ELLIS E. LONGFELLOW.
